PROPELLUTION MEANS FOR ROWBOATS

Frank W. Raicy, Portland, Oreg.

Application March 14, 1949, Serial No. 81,248

2 Claims. (Cl. 115—32)

1

My invention relates to means for propelling row boats and skiffs particularly those used for hunting and fishing. The objectives and advantages of this invention over the prior art will come to the surface as the specification progresses.

Wild game is becoming scarce and hunters are becoming plentiful as the country is opened up and better roads are made available. Ducks and geese are difficult to approach. Operators of row boats make their presence known audibly and visually because of the implements they use to move their boats and because of the gyrations they go thru in doing so. When they troll or cast for fish the turbulence created by oars frightens the fish.

To remedy the above is the principal objective of my invention. There are many other objectives such as enabling the operator to face in either direction while travelling, to propel the boat without noise or turbulence, and to propel the boat while out of sight.

The invention is illustrated in the accompanying drawings in which Fig. 1 is a vertical section thru a boat and shows the propelling apparatus in position; Fig. 2 is a plan view of the propelling apparatus; Fig. 3 is an end elevation of the propelling apparatus; Fig. 4 is an enlarged elevation of a blade; and Fig. 5 is a horizontal section on the line 5—5 of Fig. 4.

Throughout the drawings and the specification similar numerals refer to similar parts.

Fig. 1 is a vertical section thru the stern of a row boat 1 with my propelling apparatus 2 detachably secured thereto. I employ a rudder 3 provided with a tiller 4 positioned at right angles thereto. The rudder 3 is provided with an upper pintle 5 and a lower pintle 6. On the end board 7 of the boat 1 is secured the upper and lower sockets 8 and 9 spaced to receive the rudder pintles 5 and 6, respectively, whereby the rudder 3 and incidently the rest of my apparatus is pivotally attached to the boat and adapted to be turned by the tiller 4 from side to side. From the above it is evident that the whole propelling and steering apparatus may be detached from the boat as a unit by lifting it upwardly till the pintles are removed from their sockets and said apparatus may be put in operative position by reversing the operation.

The rudder 3 is not limited in configuration but in this instance it is shown as an oblong sheet of thin material extending about six inches below the bottom of the boat 1. Its upper end is formed with an extension 10 provided with a boss

2

11 on each side thereof to provide an adequate length of bearing for the hinge pin 12 on which the blade-carrying arms 13 and 14 are hinged and also to provide ample clearance for the movement of the blades 15 when in open position or on the push stroke.

10 The blades 15 are positioned within the bifurcation 16 formed in the lower ends of the arms 13 and 14 and project an equal distance on each side of said arms and are secured thereto by the screws 17 therein which pass thru the blade 15. The blades 15 are made of a circular sheet of flexible material as rubber 18 with two semi-circular pieces of spring wire 19 moulded in to provide stiffness to portions of the perimeter. The central portion 20 of the blade 15, or that portion within the bifurcation, is without reinforcement so that the blade 15 may be readily folded as is shown in Figs. 1 to 3, at 21. This folding operation of the rubber blade 15 takes place during the back stroke of the arms 13 and 14. To prevent the blade 15 from opening too far on the front or push stroke the reinforcing wire 19 has its ends 19A bent at right angles to the body portion 19B to lay against the sides of the arm 13 or 14 when the blade 15 is fully opened as it should be during said push stroke. This is clearly shown in Fig. 5, and is the preferable construction. In the upper portion of Fig. 4, the end 19A is first bent upwardly and out of the sheet of rubber 18 and then at right angles. This latter construction is also clearly shown in Fig. 1, at 22.

25 The rudder 3 has been shown cut from a single piece of material and since it is thin it has been reinforced by two side strips 23 and 23 which provide stiffness for the tiller 4 of which they form a part. Their outer ends are spread to form a fork 24 for the reception of an operating arm 25 formed with a hand grip portion 26 on each end thereof. The pin 27 journalled in the fork 24 permits the operating arm 25 to be reciprocated by the occupant of the boat. The arm 13 is shown connected to the upper end of the operating arm 25 by the bent connecting rod 28 which is hingedly connected to the arm 13 and the operating arm 25 by the hinge pins 29 and 30, respectively. In a like manner the arm 14 is shown connected to the lower end of the operating arm 25 by the bent connecting rod 31 which is hingedly connected thereto by the hinge pins 33 and to the arm 14 by the hinge pin 32. Because of the above hook-up the occupant of the boat may alternately reciprocate the blades 15 and thus move his boat forward. He may 35 do this from the seat 34 when facing in the

direction of travel or he may reciprocate the operating arm 25 from the seat 35 while facing the stern of the boat which he would probably do when casting or trolling for fish. If he wants to sneak up on ducks without being seen he may remove the seat 35 and reciprocate the operating arm 25 while lying out of sight on the floor boards 36 of the boat 1. The blades 15 are normally about 6" below the bottom of the boat 1 and never break the surface while operated hence they do not create a turbulence as do oars.

The apparatus described and shown is of the utmost simplicity yet it admits of many modifications in shape, arrangement, and adaptation, and while the prior art have been active they have not approached the subject matter of the appended claims and hence I claim all that comes fairly within their scope.

I claim:

1. In an apparatus for the propulsion of boats, a rudder having a tiller, an operating arm fulcrumed on a pin in the end of the tiller, a hinge pin carried by the rudder, a blade-carrying arm mounted on the hinge pin on each side of the rudder, a connecting rod hingedly connected to one blade-carrying arm and to one end of the operating arm, a connecting rod hingedly con-

nected to the other blade-carrying arm and to the opposite end of the operating arm, and a blade carried by each arm adapted to fold on the backward movement of its arm and open on the forward movement thereof.

2. In an apparatus for the propulsion of row boats having a pair of blade-carrying arms alternately movable forward and back, a blade formed of a sheet of rubber having opposite portions of its peripheral edge reinforced and its intervening middle portion unreinforced said reinforcement consisting of a pair of semi-circular metal members having their ends bent at right angles to the intervening portion of said blade.
